UNITED STATES PATENT OFFICE.

AUGUST MILLER, OF TAUNTON, MASSACHUSETTS.

DESIGN FOR A SPOON OR SIMILAR ARTICLE.

SPECIFICATION forming part of Design No. 30,128, dated February 7, 1899.

Application filed January 4, 1899. Serial No. 701,164. Term of patent 14 years.

To all whom it may concern:

Be it known that I, AUGUST MILLER, a citizen of the United States, residing at Taunton, in the county of Bristol and State of Massachusetts, have invented and produced a new and original Design for a Spoon or Similar Article, of which the following is a specification, reference being had to the accompanying drawings, forming part thereof.

10 Figure 1 is a front view, and Fig. 2 a back view, of my new design for a spoon.

The leading feature of my design is a long and narrow shank portion of concave marginal contour extending from the bowl of the spoon at $b b$ to a point near the outer end of the handle at $a a$ and having a double marginal bead. These beads terminate on the front side at the bowl in short outturned scrolls $b b$. On the front side, about the middle of the shank portion, there are three parallel longitudinally-arranged raised ribs $d c d$, of which the inner one, c , is somewhat longer than the other two and projects beyond them at both ends. At the outer end of the handle its contour abruptly widens to a broad end having a symmetrical marginal ornamentation of raised work consisting of a cen-

tral terminal figure e of a shape resembling in general appearance a fleur-de-lis, flanked on each side with a roll $g g$, and between this roll and the points $a a$ a raised scroll ornament $f f$, having an inturned volute at its upper end and foliated terminals at the lower end. On the back side substantially the same ornamentation appears at $e' g' f'$, but of a somewhat less elaborate character, and the marginal bead $a' b'$ is single instead of double.

On the bottom of the bowl of the spoon, near the shank, is displayed a raised symmetrical ornament h .

The leading feature of my design may be applied to other analogous plateware articles—to a fork, for instance, as suggested in dotted lines.

Having thus described my invention, what I claim is—

The design for a spoon or similar article as herein shown and described.

AUGUST MILLER.
